Primary Examiner — Richard E Chilcot*(74) Attorney, Agent, or Firm* — The Webb Law Firm**CLAIM**

The ornamental design for vegetable cutting device, as shown and described.

DESCRIPTION

FIG. 1 is an upper perspective view of a vegetable cutting device, showing my new design;

FIG. 2 is a top view thereof;

FIG. 3 is a bottom view thereof;

FIG. 4 is a front elevation view thereof;

FIG. 5 is a rear elevation view thereof;

FIG. 6 is a left side elevation view thereof; and,

FIG. 7 is a right side elevation view thereof.
